(57) **CLAIM**

The ornamental design for a hydraulic hose pair grommet, as shown and described.

DESCRIPTION

FIG. 1 is a perspective view of the hydraulic hose pair grommet according to the present invention.

FIG. 2 is a front view of the hydraulic hose pair grommet according to the present invention. The rear view is a mirror image of the front view.

FIG. 3 is a right side view of the hydraulic hose pair grommet according to the present invention.

FIG. 4 is a left side view of the hydraulic hose pair grommet according to the present invention; and,

FIG. 5 is a top view of the hydraulic hose pair grommet according to the present invention. The bottom view is identical to the top view.
